JAMES E. SNELLING, OF LOS ANGELES, CALIFORNIA, ASSIGNOR OF ONE-FOURTH TO JOHN R. REYNOLDS AND ONE-FOURTH TO DAPHNE R. REYNOLDS, BOTH OF LOS ANGELES, CALIFORNIA

MARKING GAUGE FOR MORTISED DOOR LOCKS

Application filed November 21, 1928. Serial No. 320,917.

This invention relates to gauges and deals specifically with a gauge such as may be used by carpenters for marking a door for a mortised lock.

It is common practice among carpenters, when mounting a mortised lock on a door to first wedge the door stationary by means of a chisel or other suitable means and then measure up to the proper height for either the base or the top of the lock. The lock is then held as nearly as possible in proper position on one side of the door while the marks for boring the key hole and handle hole are punched or penciled. The same operation is performed on the opposite side of the door with the result that a great many times, the marks on opposite sides of the door do not correspond. The consequence of this, when the holes are bored from each side, is to produce a crooked hole, which necessitates reaming to allow the knob to rotate freely or the other key to enter the lock.

After the sides of the door are thus marked, the edge of the door is next scored for mortising to receive the plate of the lock. Here another chance for error permits the lock to be thus positioned so that even if the knob holes and the keyholes aligned, the mortise upon the edge of the door would throw the lock out of position.

To avoid these objectionable features and in an effort to simplify and expedite carpenter work, especially in mounting locks, I conceived the idea of providing a gauge that would mark the front and both sides of the door at one and the same setting. In order to facilitate the marking, I equipped my gauge with points that are an integral part of the device which obviates the necessity of holding the gauge with one hand while searching for a pencil to make a mark, thus eliminating the possibility of a slippage and the consequent necessity of a resetting.

My invention contemplates a device that may be carried in an apron pocket and which may be readily and accurately used to indicate the points for boring a door to mount a mortised lock.

Having set forth the principal objects

and advantages of my invention, recourse is now had to the drawings, in which:

Fig. 1 is a center line section of my device, seen on line 1—1 of Fig. 2;

Fig. 2 is an end elevation;

Fig. 3 is a perspective of the same;

Fig. 4 is a fragmentary perspective showing the marks upon a door.

Referring to the drawings, my device is shown comprising a channel shaped member A having wings B hingedly mounted as shown at 12 on the legs 11 of the channel. The hinge in this instance, is shown as stamped out of the material of the channel and wings, but I do not confine myself to this structure as the hinges may be mounted independently.

The wings B are equipped with marker points 13 and 14 which are shown as stamped from the metal of the wing itself. This structure, however, is optional as the marker points may be soldered on, and equal results obtained thereby. As shown in Fig. 1, the top and bottom edges of the leaf B are cut away as illustrated at 16 to bring the edges even with the points 13 and 14 as indicated by the dotted lines.

Also the side of B is cut back as shown at 15 to bring it flush with the line y—y passing through the points 13 and 14. The purpose of cutting back the edges as described, is to permit placing the points on a line, such as for instance, the height line on the door indicating the location of the knob.

The web 10 of the channel A is equipped with markers 20 at the upper and lower ends thereof. These markers indent a line on the edge of the door, which indicates the top and bottom respectively, of the mortise for the plate of the lock, while their length would show the width of the mortise. They also serve as stops for bringing the markers 13 and 14 into their proper position. Intermediate these markers, is a plurality of aligned points which upon pressing into the wood of the door, make a series of aligned indentations, each indicating the point at which a hole should be bored to form the mortise for the lock. It will be understood that the number of such markers upon each gauge

depends upon the size of the lock and the size of the bit used in boring; it being only necessary that the holes are sufficiently close to permit the sides of the mortise to be smoothed up with a chisel or other suitable tool. It is also understood that these markers, while in this instance are shown as being struck from the metal, may equally as well, be soldered or riveted to the web 10 of the channel A.

10 To give the device a neat workmanlike appearance, I cut away the tip and bottom edges of the legs 11 of the channel A as shown at 18.

In using my device, the height of the knob 15 is first measured; the door being left free to swing. My device with the wings B set as shown at k, k is slipped over the edge of the door and brought to the proper height by bringing the edge 16 to the line showing 20 the height of the knob. A sharp blow by the hand on the back of the device serves to make the marks on the edge of the doors, after which the wings B are either pressed into place or slapped into place by the hand. It 25 is manifest from this that the operation is simple and accurate. The accuracy is obtained by causing the marks on opposite sides of the door to absolutely correspond as well as insuring that the mortising on the edge 30 of the door will correspond with the side markings.

In Fig. 4, I show the edge of a door having the markings as they would appear after using my gauge. Mark 13' locates the bore 35 for the knob handle of the lock and mark 14' locates the point of boring the keyhole. The indented lines 20' denote the top and bottom of the mortise for the plate of the lock, while the aligned marks 21' indicate the points 40 for boring for the mortise for the lock body. It is understood that there is, on the opposite side of the door, diametrically opposite marks 13' and 14', another set identical in location. It is also understood that all these marks 45 are made at one setting of the gauge.

The operation is simple inasmuch as the only measuring necessary is to obtain the height of the knob, and this may be done by having a marking stick cut the proper length. The remaining operations are a few simple 50 movements of the hands. By making the device symmetrical, I eliminate any chance of its being used improperly; there is no top nor bottom rightfully speaking. Consequently the device may be used reversibly, 55 and the results would be the same.

When not in use, the wings B of the device are closed as shown at L, L which serves to keep the points protected as well as decrease 60 its size for pocket carrying.

Having set forth and described one embodiment of my invention, I am aware that certain modifications and refinements may be incorporated therein. For instance, it is 65 manifestly clear that fixed dimensions will

not serve all locks. I therefore, reserve the right to adopt such alterations in the nature of refinements and modifications that do not depart from the spirit of the specifications nor the purview of the appended claims.

70 I claim:

1. A marking gauge of the character described comprising a unitary channel shaped member for positioning astride the edge of a door, wings hingedly mounted upon the legs 75 of said channel shaped member, markers upon said wings for marking upon opposite sides of a door the knob hole and the keyhole for a lock, markers on the ends of the channel shaped member for marking the mortise for 80 the plate of the lock and for marking the width of the mortise for the lock on the edge of the door, said markers serving as stops when abutting against the edge of the door to bring the markers on said wings into their 85 proper position.

2. A marking gauge of the character described comprising a unitary channel shaped member for positioning astride the edge of a door, wings hingedly mounted upon the legs 90 of said channel shaped member, markers upon said wings for marking upon opposite sides of a door the knob hole and the keyhole for a lock, markers on the ends of the channel shaped member for marking the mortise for 95 the plate of the lock and for marking the width of the mortise for the lock on the edge of the door, said markers serving as stops when abutting against the edge of the door to bring the markers on said wings into their 100 proper position, and aligned points projecting inwardly from the web of said channel shaped member projecting therefrom beyond the plane of the markers on the ends of said channel shaped member for forming a series 105 of aligned indentations on the edge of the door.

In testimony whereof, I have affixed my signature.

JAMES E. SNELLING.
